HAIR TONIC

Domenico Caimi and Agostino Caimi,
Philadelphia, Pa.No Drawing. Application July 12, 1937,
Serial No. 153,202

2 Claims. (Cl. 167—87)

This invention relates to the manufacture of hair tonics, antiseptic skin lotions and the like, and has particular reference to the combining of alcohol and olive oil.

5 Alcohol and olive oil has no affinity. If olive oil is introduced into alcohol and violently agitated, the oil will appear to have been dispersed, but upon the standing of the combined mass for a short period of time, the separation will be 10 complete.

Alcohol and olive oil each have great virtue in hair tonics and lotions of various kinds, and it is highly desirable to provide both these ingredients in such classes of goods.

15 Over a period of some years, experiments were made in an endeavor to combine alcohol and olive oil into a basic compound having not only the inherent virtues thereof, but to constitute a vehicle for carrying other ingredients for the 20 parts to be treated.

The object, therefore, of the present invention is to combine alcohol and olive oil in a perfect mixture.

Another object of the invention is to provide 25 an efficient hair tonic using combined alcohol and olive oil as a base.

Another object of the invention is to provide an efficient antiseptic skin lotion using combined alcohol and olive oil as a base.

30 Many hair oils now on the market contain castor oil, although some have been erroneously labeled as containing "olive oil." Castor oil has an affinity for alcohol. Olive oil has not. In order, therefore, to form a combined mixture 35 of alcohol and olive oil, it is necessary to introduce into the combination, some ingredient which will act to cut the olive oil into the alcohol. It has been found that kerosene introduced into combined alcohol and olive oil and agitated will 40 permit the alcohol and olive oil to combine into a chemical mixture.

Taken as a base, the combined alcohol and olive oil, with its kerosene content, may be used for many purposes to which less effective mixtures have been formerly applied.

45 While no limitations are to be assumed by the following formula, we have found that a basic material may be produced by using ingredients in the following proportions:

	Gallons
Alcohol	100
Olive oil	35
Kerosene	50

55 The kerosene most desirable for use in this com-

bination is odorless kerosene, and when the foregoing ingredients have been thoroughly mixed in the proportions stated, it will be found that the olive oil has been dispersed throughout the alcohol and even when the same has been left to stand for a period of several months, no separation has been apparent.

The foregoing base has been found to be of unusual value in the formation of hair tonics. The ingredients introduced into the base just described are castor oil and resorcin with just sufficient scent or perfuming matter to give the mixture a pleasing odor.

When used as a hair tonic, it has been found that the following formula produces an efficient 15 hair tonic, but this formula is given by way of illustration, and is not intended to constitute a limitation:

Alcohol	gallons	100	20
Olive oil	do	35	
Odorless kerosene	do	50	
Castor oil	do	20	
Resorcin	lbs.	2	
Perfume to suit			25

Advancing from the mixture designated as a hair tonic, it has been ascertained that antiseptic skin lotions of great potency may be produced from the base hereinbefore described. In the manufacture of the antiseptic skin lotion it has 30 been found that the following formula produces a most efficacious lotion:

Alcohol	gallons	100	
Olive oil	do	35	35
Odorless kerosene	do	50	
Castor oil	do	20	
Resorcin	lbs.	2	
Betanaphthol	lb	1	
Para tertiary amyl phenol	lbs	4	40
Perfume to suit			

The lotion just above described is given in terms of approximate amounts, and the applicants herein do not limit themselves specifically to these amounts, but use this formula as illustrative only, and a formula which has proven to give desired results.

Both the hair tonic and antiseptic skin lotion made from the base hereinbefore described have been subjected to many experiments and tests, 50 and are recommended by medical authorities.

Of course, the alcohol and olive oil base herein described is susceptible of wide use apart from the hair tonic and antiseptic skin lotion herein described, and the hair tonic and skin lotion may 55

be modified in various ways without departing from the invention herein described and hereafter claimed.

The invention is hereby claimed as follows:

1. A hair tonic comprising a solution of ingredients in the following approximate proportions: alcohol 100 gallons; olive oil 35 gallons; and kerosene 50 gallons.

2. A hair tonic comprising alcohol, olive oil and kerosene, the kerosene being present in an amount sufficient to miscibilize the alcohol and olive oil to form a permanently clear solution.
